Primary Examiner — Karen E Eldridge Powers*(74) Attorney, Agent, or Firm* — Levine & Mandelbaum(57) **CLAIM**

I claim the ornamental design for a star-shaped crayon, as shown and described.

DESCRIPTION

FIG. 1 is a perspective view from the top, right side and front of a star-shaped crayon showing my new design.

FIG. 2 is front elevational view thereof.

FIG. 3 is rear elevational view thereof.

FIG. 4 is right side elevational view thereof.

FIG. 5 is left side elevational view thereof.

FIG. 6 is top plan view thereof; and,

FIG. 7 is bottom plan view thereof.

The stippling shown on the crayon portions around the perimeter are provided to represent a contrast of color.
